W. H. BURR.

ADJUSTABLE GUIDE BOARD FOR VEHICLE ROUTES.

APPLICATION FILED JAN. 9, 1918.

1,285,925.

Patented Nov. 26, 1918.

By

D. K. Bryant.
Attorney

UNITED STATES PATENT OFFICE.

WILLIAM H. BURR, OF ROCHESTER, NEW YORK.

ADJUSTABLE GUIDE-BOARD FOR VEHICLE-ROUTES.

1,285,925.

Specification of Letters Patent. Patented Nov. 26, 1918.

Application filed January 9, 1918. Serial No. 210,958.

To all whom it may concern:

Be it known that I, WILLIAM H. BURR, a citizen of the United States of America, residing at Rochester, in the county of Monroe and State of New York, have invented 5 certain new and useful Improvements in Adjustable Guide-Boards for Vehicle-Routes, of which the following is a specification.

This invention relates to certain new and 10 useful improvements in adjustable guide-board for vehicle routes.

The primary object of the invention is the provision of a guide board adapted for ready positioning along any roadway or 15 line of travel adapted for visually indicating conditions of travel at advanced points along the route.

A further object of the device is the arrangement of a route sign that possesses simplicity, utility and durability, adapted for 20 mounting upon any convenient support for indicating the distance and direction of a certain locality as well as exigencies of travel conditions at intermediate points along the 25 way, whereby the traveler may be on the lookout for such occurrences as dangerous road crossings and railroad crossings in the direct order in which the same will be encountered.

30 A still further object of the invention is the arrangement of a distance and direction sign provided with interchangeable indicia of travel conditions, whereby the sign may be arranged to correctly indicate succeeding roads and crossings upon any line 35 of travel, such indications being also readily changeable in the event of a change in such conditions.

With these general objects in view and 40 others that will appear as the nature of the invention is better understood, the same consists in the novel construction, combination and arrangement of parts hereinafter more fully described, illustrated in the accompanying drawing, and then claimed.

In the drawing forming a part of this application and in which like designating characters refer to the corresponding parts throughout the several views,

45 Figure 1 is a perspective view of the device operatively positioned upon a post.

Fig. 2 is an enlarged horizontal longitudinal sectional view of a portion thereof taken upon line 11—11 of Fig. 3, and

50 Fig. 3 is an elevational view of the said portion of the device.

A device of the nature hereinbefore indicated is especially serviceable for automobile drivers in giving advance information respecting the distance and direction of a 60 destination as well as a warning of dangerous places such as curves in road crossings and also railroad crossings as well as intersecting and branch roads.

The device broadly consists of a sign 65 board 10 preferably in the form of a large arrow which may be made of metal and suitably colored if desired. An advance point of travel such as a city is indicated upon the rear plate portion 11 of the arrow 70 such as New York while the distance from the sign to such city is also indicated thereon as at 12.

The sign board 10 is readily mounted upon any support as the post 13 conveniently positioned at the side of the roadway. It will be understood that the said board may be mounted in this manner upon any desirable support and if the occasion requires, the sign may be bent as at 14 in angular arrangement to accurately indicate the direction of the destination, with the triangular point member 17 pointing out the path of travel.

A plurality of indicators 18, 19, 15, 20, 85 18', 21 and 22 are arranged for use upon the reduced shank or shaft portion 23 of the board 10, struck up receiving sockets or bands 24 being arranged upon the shank for the interchangeable reception thereof. Indicator 18 is L-shaped and points toward the left which shows that a cross road from the left will meet the main road at a point farther on, but that the driver should keep straight ahead in order to reach New York. 95

The next indicator 19 shows that a railway crossing will then be met and this indicator may be colored red and marked R. R. The indicator 15 is any number being herein shown as 9, and designates the number of 100 miles to the next service station. The next indicator 20 shows that a road crosses the main line of travel diagonally while 18 shows a cross road entering from the right; the indicator 21 shows that there is a dangerous 105 railroad or other crossing arranged at right angles to the route of travel; while indicator 22 shows the presence of a diagonal branch road to be found therebeyond.

The indicators 18 may be arranged to 110 point either toward the right or left to show that a future road branches either to the

right or left from the line of travel, while the indicator 20 which is T-shaped in form with an oblique head may be reversely positioned for showing the arrangement of the 5 diagonal cross road. In a like manner, the indicator 22 may be reversed for showing in which direction the angular cross road extends from the line of travel.

In this manner it will be apparent that a 10 code language is arranged for use upon road signs that may be readily understood by the driver of vehicles passing over the route so that troublesome points ahead may be safely guarded against. Indicator 19 may indicate 15 a dangerous curve ahead if desired and this indicator may be slightly curved or bent as herein indicated by dotted lines for showing the character of such curve. Any of the indicators may be colored if desired while 20 these may also contain words or numbers stating what they indicate, or may be in the form of code letters or figures if desired.

This sign board is placed in an exposed location facing the direction from which the 25 traveler would approach at the right hand side of the road so that the same may be readily read after the manner of a guide book. Every possible dangerous condition to be approached may be indicated and anticipated. A route book might also be employed in connection with my system of sign 30 boards thereby constituting a form of general road directory. The bands 24 may be arranged with indented retaining lugs 25 for 35 seating within similar recesses 26 in the several indicators, thereby maintaining the indicators properly positioned upon the board 10 although readily removable for interchanging whenever desired.

40 A reinforcing wire or bar 16 is arranged longitudinally on either side of the sign or shaft portion 23 secured through struck up loops 27 formed in the shaft, the said bar overlying the bands 24, tightening the same 45 upon the indicators as well as preventing the shaft from bending by the action of the wind or other causes.

While the form of the invention herein shown and described is believed to be the 50 preferable embodiment thereof, it is nevertheless understood that minor changes may be made therein without departing from the spirit and scope of the invention as claimed.

What I claim as new is:—

55 1. A route sign comprising a direction indicating means and a plurality of indicators thereon depicting road conditions at distant points.

60 2. A route indicator comprising a destination direction indicator and a plurality of differently formed indicators mounted thereon corresponding in meaning to distantly positioned conditions of travel upon the route designated by the direction indicator.

65 3. A device of the class described comprising

ing a sign board adapted for indicating the direction of a distantly positioned destination upon the route of travel and indicators adapted for designating different conditions of travel at distant points upon the route 70 successively positioned upon the board in the direct order of the occurrence of such conditions from such board in the direction of travel indicated thereby.

4. A device of the class described comprising a board adapted for arrangement adjacent a route of travel for indicating the direction and distance of a stated destination, and differently shaped means interchangeably and detachably associated therewith 80 adapted for indicating conditions of travel to be encountered along the route of travel toward such destination.

5. A device of the class described comprising a board adapted for arrangement adjacent a route of travel for indicating the direction and distance of a stated destination, and differently shaped indicators carried by the board adapted for indicating different conditions of travel along the route 90 and successively arranged upon the board in the order of occurrence of such conditions upon the road in the direction indicated by the board.

6. A device of the class described comprising an arrow-shaped sign board adapted for pointing in the direction of a given destination along a route of travel, differently formed indicators carried by said board adapted for designating cross roads, branch 100 roads, dangerous curves and railway crossings arranged in the order in which such conditions of travel occur upon the route in the direction indicated by the board.

7. A sign board for automobile routes 105 comprising a distance and direction indicator for a designated point upon the line of travel, separate indicators for different conditions of travel upon the route in the direction indicated and detachable mounting 110 means therefor.

8. A sign board for automobile routes comprising a distance and direction indicator for a designated point upon the line of travel, separate indicators for different conditions of travel upon the route in the direction indicated, detachable mounting means therefor, the said distance and direction indicator being flexible and mounting means therefor adapted for maintaining the said 120 direction and distance indicator suitably bent conforming to the requirements of the road.

9. A device of the class described comprising an arrow-shaped sign board formed 125 of sheet metal adapted for pointing in the direction of a designated destination, fixed mounting means therefor, the said board having struckup loops arranged with indented lugs and differently shaped indica-

tors adapted for detachable reception within the said loops contacting the said lugs adapted for selectively indicating future conditions of travel along the route in the 5 direction indicated by the board.

10. A device of the class described comprising a direction indicating board, L-shaped indicators adapted for mounting thereon pointing in either direction for 10 designating right or left hand branch roads to be passed in travel in the direction indicated by the board.

11. A device of the class described comprising a direction indicating board, L-shaped indicators adapted for mounting thereon pointing in either direction for designating right or left hand branch roads to be passed in travel in the direction indicated by the board, and T-shaped indicators 20 carried by the board having angularly positioned portions adapted for positioning in directions for indicating intersecting roads along the line of travel.

12. A device of the class described comprising a direction indicating board, L-shaped indicators adapted for mounting thereon pointing in either direction for designating right and left hand branch

roads to be passed in travel in the direction indicated by the board, T-shaped indicators 30 carried by the board having angularly positioned portions adapted for positioning in direction for indicating intersecting roads along the line of travel, and differently colored straight and curved indicators mounted upon the board for designating railroad crossings and curved indicators mounted upon the board for designating railroad crossings and curves along the road of travel. 40

13. A device of the class described comprising an arrow shaped sheet metal sign board having an attaching portion and an angularly bent pointed shaft portion, the said shaft having a row of struck up receiving bands and struck up loops positioned outwardly of said row of bands, road condition and distance indicators positioned within said bands and a reinforcing rod arranged longitudinally of the shaft secured 45 within said loops and forcibly contacting said bands, whereby said indicators are retained therein. 50

In testimony whereof I affix my signature.

WILLIAM H. BURR.
